UNITED STATES PATENT OFFICE.

ADOLPH N. WALSTAD, OF TACOMA, WASHINGTON.

SUBGRADE TEMPLATE.

Application filed August 20, 1925. Serial No. 51,521.

This invention relates to tools for use in grading roads and especially to the template to which the subgrade is to be brought, and has for its objects to provide a strong and substantial tool adapted to be drawn over the roughly finished subgrade to bring the shape of the subgrade to the proper form and elevation, as required by the particular specifications to which the road is being built, and in thus being drawn over the ground it will smooth the said subgrade, taking off its high spots and filling its depressions and thus materially aid in speeding the work of preparing the said subgrade surface. Other objects are to provide such a tool which is adjustable for roads of various widths; or for various thicknesses of paving; or for various heights of crown; or for various depths of shoulder. Another object is to provide such a tool which, with suitable accessories, can also be used in forming the subgrade of a curved road wherein the width, the crown, and the superelevation or banking may be changed from point to point in accordance with the specifications and without changing the template from point to point. Another object is to provide a template which may be used in widening a half-width road to a full-width road. Another object is to provide a simple, strong and adaptable tool which is practical for use in substantially all the conditions met with in constructing the subgrade of a road.

I attain these and other objects by the devices and arrangements illustrated in the accompanying drawings, in which—

Fig. 1 is a front elevation of my device in use on a full-width straight roadway; Fig. 2 is a similar view showing its use for widening a half-width roadway to a full-width roadway; Fig. 3 is a similar view as arranged for making the inner half of a curved and banked roadway; Figs. 4, 5 and 6 are front elevation, cross-section, and plan, respectively, of one end of said improved tool; Figs. 7 and 8 are a cross-section and front elevation, respectively, of the central portion of such a tool, showing the adjustable crown piece.

Similar numerals of reference refer to similar parts throughout the several views.

In modern highway building it is customary to specify that the soil beneath the paving material be first brought to a required form at a certain distance below the level

of the finished pavement at all points in the cross-section of the road, except along the edges thereof where the said distance is increased in order to give the pavement a greater thickness along its edges; this edge portion is called the shoulder of the paving. Also it is customary to require that the paving, and therefore its foundation, or subgrade, be at a slightly higher elevation along the center of the roadway, thereby giving a crown to both the roadway and its subgrade. This latter requirement is, however, usually modified when the roadway curves; for instance, in some cases, it may be specified that the crown begin to flatten at a point say fifty feet before the curve begins and gradually disappear into a straight banked section shortly after the curve, proper, has begun. Also, it is quite customary to widen the roadway in accordance with the sharpness of the curve, said widening being gradually increased from the point where the crown begins to decrease to the middle point of the curve, or in long curves to a point about two-hundred feet from the beginning of said widening; in some cases said widening being made on the inside of the curve while in others it is required to be on the outside thereof. Also, on all curved roadways it is usual to bank the roadway by giving a superelevation to its outer edge, said superelevation starting at said point about fifty feet before the curve is reached. Also, when a half-width of the roadway has been built, it is usually required that tie or reenforcing rods be left extending from the completed side of the road whereby the remaining half-width may be tied thereto when it is built. Therefore, in view of these practical conditions in road building, in order for a subgrade template to be of practical utility and to make it a permanent tool in the equipment of a road contractor, it is necessary, first, that it be extensible to be applicable to various widths of road; second, adjustable to various degrees of crowns; third, its shoulder portion must be removable and adjustable to permit its replacement or adjustment to form shoulders of different depth or width; fourth, it must be possible to demount a half of its length and to substitute therefor a special shoe and fitting to permit its use in spite of the extending tie rods; fifth, the crown attachment must be detachable from the main portion of the template in order that a special straight edge may be

substituted, said straight edge being used for the merging of the crowned road with the flat-banked road, and a special shoe being attached to said straight edge, said shoe being adapted to take care of the variations in width of the road at curves; and sixth, it is necessary that the lower edge of said tool be straight, stiff, and strong enough to stand the rough usage incident to its handling and use in practical road building and to shave off the high points of the subgrade and fill any depressions therein. My device fulfills all of these conditions and is highly practical in all its features.

Referring to the drawings, it will be seen that the main length of the template comprises two complementary lengths of angle-iron 1, having their vertical faces 2 downward and in front, and the other face 3 horizontal and on top (Fig. 5). Each angle-iron 1 is about eight-feet-eight-inches long for a template for use on eighteen to twenty foot highways. The outer end of the angle-iron 1 is provided with a removable and adjustable shoulder plate 4 and with a bearing shoe, as hereinafter described. The shoulder plate 4 is trapezoidal in shape and has its inclined edge extending below the edge of the vertical face 2 of the angle-iron 1 to which it is attached, the distance said edge extends below said gage edge of the angle-iron 1 being determined by the adjustment of the securing bolts 5 by which it is attached to the face 2, in accordance with the specifications of the road being built. This adjustment may be made by passing the bolts 5 through slots in the face 2. The outer edge of the angle-iron 1 and of said shoulder plate 4 is normally about one-and-one-half inches from the grade ribbon 6 of the road bed, to allow for the stakes holding the said grade ribbon 6 in place. A bracket 7 is secured to the front side of the face 2 of the angle-iron 1, said bracket forming a horizontal extension of the upper face 3 of the said angle-iron. A carrier shoe 8 is secured to the upper face 3 and to the said bracket 7, by means of bolts 9 and is adjustable relatively to said parts by the insertion of more or fewer separators or washers 10 on the said bolts 9 between the shoe 8 and the top surface of the part 3 or bracket 7. The shoe 8 extends out horizontally from the end of the angle-iron 1 to ride on the grade ribbon 6 of the roadway, said shoe extending laterally on each side of the axis of the angle-iron, but a greater amount towards the front than towards the rear thereof (Fig. 6). The shoe 8 is constructed of stiff and strong material and may be suitably reinforced to attain this end.

In order to guide the operation of the template I provide a pair of control handles at each end. These handles 11 are similar to plow handles and are pivoted at their

lower ends to a lug 12 on the upper side of the part 3 of the angle iron, and their outer ends are supported in adjustable elevation by means of the two standards 13. The standards 13 are pivoted at their lower ends 70 to the upper side of the said shoe 8 and each is fastened to one of said handles 11 by means of a removable bolt. A plurality of holes are provided in the standards 11 whereby the handles may be secured at different heights to suit the conditions of the work (Fig. 4). A diagonal brace 14 connects the two standards 13. A horizontal bar 15 connects the two handles 11 to brace them apart.

The template is moved along the ground by means of cables 16 (Fig. 6) attached to the loop fittings 17 secured to the front face 2 of the angle iron 1. These loop fittings may be shifted to any of several positions, 85 in accordance with the work to be done and the form of the template in use, as shown in Figs. 1 and 2.

As above stated the angle-iron 1 extends less than one-half the width of the narrowest roadway on which it is to be used. When the roadway is full-width and straight (Fig. 1) the template comprises two complete angle-irons with their end attachments as above described, joined together by 90 a central crown piece. This piece may be made with its two portions permanently set at a definite angle, vertically, or it may be adjustable as shown in the drawings (Figs. 1, 7 and 8). In either case it is of considerable length and each end is provided with a plurality of sets of bolt holes 18 (Fig. 8) arranged so that the angle-irons 1 may be attached thereto at any of several positions, thus controlling the distance between the shoes 8 to agree with the particular width of the roadway to be built. The center, or crown piece, therefore comprises two L-shaped sections 19 and 20, each secured to one of the two angle-irons 1 by means of 105 bolts passing through both faces 2 and 3 thereof and through the holes 18 in the said parts 19 and 20. The two parts 19 and 20 may be hinged together by means of the horizontal pintle 21 (Fig. 7), in the usual 110 way, and may be set at any angle to each other and held thereat by clamping the parts together by the bolts 22 which pass through holes and slots 23 therein, or by any other 115 suitable means. Thus the crown may be made to conform to various specifications without having to make a new template, or to provide a number of said central pieces.

If, however, the roadway is not straight, 125 the said crown piece is removed from the angle-iron 1 and a straight angle-iron union 24 (Fig. 8) is provided, joining said angle-iron 1 with another angle-iron 1 to which a special end shoe 25 is fastened. This end 130

shoe 25 extends a considerable length along the axis of the template and outward therefrom, thus providing a means of using the template on the varying width of the roadway required by the specifications for a curved road. This straight template is used from a point some distance away from the point of beginning of the curve, instead of the above-described crowned template, by placing certain supplementary blocks 26 on top of the grade ribbon 6 (Fig. 3). At the point where this straight template is started, the block 26 is thickest and tapers therefrom thinner and thinner. Corresponding blocks 26 are used on the two sides of the road and complementary templates are used, but only one set of blocks and one template is in use at a time. The use of these straight templates and the blocks 26 therefore gradually washes out the crown as the curve is approached. Also, at this same place the straight template is used, the superelevation of the outer side ribbon 6 begins and continues at an increasing rate reaching a maximum at a point say fifty feet after the curve has been reached. Also, the width of the roadway begins to increase at the same point where this straight template is used and continues to increase reaching a maximum about one-hundred-and-fifty feet after the curve has been reached. As the road widens the ribbon 6 rides further and further out on the special shoe 25.

When a half-width of roadway has been built first and, subsequently, the roadway is to be made full width, the single length of angle-iron 1 is used with a special fitting 27 on the end thereof adjacent to the completed roadway. It is usually required, when this condition exists, to leave certain tie bars 28 extending out from the edge of the completed half-width roadway 29, and I therefore provide the said fitting 27 with a slot 30 adapted to permit it to pass the said bars 28. The fitting 27 is provided with a shoe 8, similar to that already described.

Thus it will be seen that I have provided a tool which, with its several accessories, may be used in a great variety of conditions found in road building, permitting changes in its design, as to its crown and its shoulders, its width, and its specified variations in width and crown on its curves. Throughout all these conditions the same parts are used as to the respective portions of the road being made, the only difference being, in the case of the curved road, that the half road is gaged at one time and with one template while the other half of the road is gaged with the other complementary part of the template at a subsequent time, and that therefore the half of the template not in use as a template, does not come in contact with the subgrade and varies somewhat in form of its shoe, over the standard form of

shoe, and is not provided with a shoulder plate. Also, it will be seen that changes in the thickness of the paving may be had by adjusting the connections between the shoe, which engages and rides on the grade ribbon, and the main angle-iron of the template, thus raising or lowering the template and forming the subgrade at a higher or lower relative elevation. 70

Having, therefore, described my invention 75 what I claim is:—

1. A subgrade template comprising a main piece; a detachable shoulder-forming plate attached to the outer end thereof; a grade-ribbon gage shoe mounted on the said 80 end, above said shoulder plate, and riding on one grade ribbon of the roadway; and a flat extension mounted on the inner end of said main piece and adapted to slide longitudinally and laterally on the other grade 85 ribbon of the roadway, thereby permitting the second grade ribbon to vary in distance from the first grade ribbon, whereby the template is guided along the roadway and whereby its form is controlled to form the 90 desired incline of the subgrade from the center to the edge on straight or curved roadways or constant or varying widths.

2. A subgrade template as set forth in claim 1, wherein said main piece comprises 95 an angle-iron, positioned with one edge engaging the subgrade; and wherein said center guiding means comprises, in part, another angle-iron secured within the angle of said main piece and continuing the line of its 100 lower edge.

3. A subgrade template as set forth in claim 1, wherein said center guiding means, mounted on the inner end of said main piece, is adjustably secured thereto, whereby the 105 template may be used for full or half width roadways of various widths.

4. A subgrade template as set forth in claim 1, wherein said center guiding means, mounted on the inner end of said main piece, 110 is adjustable in form whereby the incline or crown of the subgrade may be altered.

5. A subgrade template as set forth in claim 1; together with means for attaching hauling cables to the main piece whereby 115 the template is slid on the grade ribbons; and with adjustable guide handles mounted on the outer end of the main piece, whereby its motion may be controlled.

6. A subgrade template comprising a pair 120 of main pieces, positioned on opposite sides of the center of the template and comprising the major portion thereof; a pair of grade-ribbon gage shoes, mounted on the outer ends of said main pieces and each adapted to ride on the respective grade ribbons to guide the template along the roadway; a central crown member composed of two overlapping pieces, each secured to the inner ends of the corresponding main pieces, and hinged together 125 130

at their upper edges; and clamping means positioned near their lower edges and adapted to hold said pieces together in adjusted relation, whereby the incline of said main pieces and the crown of the roadway is adjustably determined.

7. A subgrade template comprising a pair of main pieces, positioned on opposite sides of the center of the template and comprising the major portion thereof; a pair of grade-ribbon gage shoes, mounted on the outer ends of said main pieces and each adapted to ride on the respective grade ribbon to guide the template along the roadway; and a central crown piece, secured at its two ends to the inner ends of said main pieces, whereby the incline of said main pieces and the crown of the roadway is determined.

8. A subgrade template as set forth in claim 7, wherein said main pieces and crown

piece are angle-iron in form, and wherein said crown piece lies within the angle of said main pieces, and its lower gage edge forms continuations of the lower gage edges of said main pieces to the center of the roadway.

9. A subgrade template as set forth in claim 7, wherein said crown piece is provided with a plurality of sets of bolt holes at corresponding positions on the two sides of the center, and the main pieces are each provided with a single set of corresponding bolt holes; together with bolts passing through the holes in main pieces and the crown piece to secure the parts together in any one of a plurality of positions whereby the same template may be used for roadways of various widths.

ADOLPH N. WALSTAD.
